UNITED STATES PATENT OFFICE.

HARRY M. SALYER, OF NEW YORK, N. Y., ASSIGNOR TO LUDWIG & CO.,
OF SAME PLACE.

AUTOMATIC CONTROLLING-VALVE.

SPECIFICATION forming part of Letters Patent No. 678,427, dated July 16, 1901.

Application filed December 20, 1900. Serial No. 40,485. (No model.)

To all whom it may concern:

Be it known that I, HARRY M. SALYER, a citizen of the United States, and a resident of the city of New York, borough of the Bronx, in the county of New York and State of New York, have invented certain new and useful Improvements in Automatic Controlling-Valves, of which the following is a specification.

10 The object of my invention is to provide a new and improved automatic controlling-valve for pipes containing a fluid under pressure, such as the steam-pipe conveying steam to an engine or a compressed-air pipe and the like.

15 In the accompanying drawing one type of my improved automatic controlling-valve is shown in section.

The valve-casing A is provided with a partition B, from which a hub C extends, in which hub a chamber D is formed. This chamber is open at the top and can be closed by a valve E, resting on the top of the hub and provided with a stem F, which extends through the hub. A lateral neck G extends from the exterior of the casing to the chamber D, and an opening H in the side of the casing is in communication with that part of the casing above the valve E. When the valve E is raised, 20 more or less, the fluid under pressure—such as steam, compressed air, &c.—can pass from a tube connected with the neck G through said neck, the chamber D, the upper part of the casing A, and out through the opening H into a pipe H', connected with said opening. When the valve E is seated, such communication is interrupted. A diaphragm J is secured in the casing A below the partition B and is attached to the lower end of 25 the valve-stem F. The valve-stem F has a duct or passage K extending from the space below the diaphragm J to the space between the diaphragm J and partition B, and this duct can be adjusted in size by means of a screw L, extending through the valve-stem F from the upper end. A small hole M in the partition B establishes communication between the space between the partition B and diaphragm J and the neck G. The casing A has a neck N below the diaphragm J, and this neck is connected with one or more

tubes O, which are normally closed at their outer ends, but can be opened automatically or at will. The pressure existing in the neck G and chamber D—say one hundred pounds per square inch, more or less—acts on the under side of the valve E and lifts the same as long as no greater force serves to keep this valve on its seat. This same pressure exists in the space between the diaphragm J and 55 partition B, as the hole M establishes communication between such space and the neck G. The same pressure exists in the space below the diaphragm as long as the tube or tubes O are closed, as the duct K establishes communication between the space above the diaphragm and the space below the diaphragm. The diaphragm J is thus held in equilibrium as long as the space below the diaphragm is closed—that is, as long as the pressure cannot escape from the same—and as long as the diaphragm is held in equilibrium the pressure acting upward on the valve E can open the same and hold it open more or less.

If any one of the tubes O is opened, the 75 pressure on the under side of the diaphragm J at once decreases and the equilibrium of the diaphragm is destroyed.

As the area of the diaphragm J is much greater than the area of the under side of the valve E and as the pressure on the upper surface of the diaphragm and under side of the valve per inch is the same and, as stated, the pressure on the under side of the diaphragm is less than that on the upper side, 80 it follows that the pressure on the upper surface of the diaphragm holds the valve on its seat and the passage of the steam or compressed air through its conduit is stopped. For example, one of the tubes O could extend to the captain's bridge on a steamer, another to the engineer's station, and another to an automatic governor, which operates to open the tube O when a certain maximum speed is reached.

95 The engineer or captain or other person could at once stop the ship's engine by opening the end of a tube O, providing my improved valve is located in the main steam-pipe, or the engines could be stopped automatically by the governor.

Having described my invention, what I

claim as new, and desire to secure by Letters Patent, is—

1. The combination with a valve-casing, having a partition provided with a hole and 5 with a hub, in which hub a chamber open at one end is formed, which chamber is in communication with the exterior of the casing, of a valve for closing said chamber, a diaphragm secured in the casing below the partition and 10 connected with the stem of the valve, a duct being provided for establishing communication between the space above and below the diaphragm and a tube connected with the space between the diaphragm and the bottom 15 of the casing, substantially as herein shown and described.

2. The combination with a valve-casing having a partition provided with a hole and with a hub, in which a chamber, open at one 20 end is formed, which chamber is in communication with the exterior of the casing, of a valve for closing said chamber, a diaphragm secured in the casing below the partition, and connected with the stem of the valve, said 25 valve-stem being provided with a duct establishing communication between the space above and below the diaphragm and a tube connected with the space between the diaphragm and the bottom of the casing, substantially 30 as herein shown and described.

3. The combination with a valve-casing having a partition provided with a hole and with a hub, in which a chamber, open at one end is formed, which chamber is in communication 35 with the exterior of the casing, of a valve for closing said chamber, a diaphragm secured in the casing below the partition, and connected with the stem of the valve, said valve-stem being provided with a duct establishing 40 communication between the space above and below the diaphragm, means for adjusting the size of this duct and a tube con-

nected with the space between the diaphragm and the bottom of the casing, substantially as herein shown and described. 45

4. The combination with a valve-casing, of a valve in the same, a diaphragm larger than the valve, in said casing, connected with the stem of the valve, means for producing the same fluid-pressure on the under side of the 50 valve and on both sides of the diaphragm and means for reducing at times, the pressure on the under side of the diaphragm, substantially as herein shown and described.

5. The combination with a valve-casing, 55 having a chamber formed therein, of a valve for closing said chamber, a diaphragm held in said casing and connected with the stem of the valve and means for producing the same fluid-pressure in the casing, against the 60 under side of the valve and on both sides of the diaphragm and means for reducing at times the pressure on the under side of the diaphragm, substantially as herein shown and described. 65

6. The combination with a valve-casing having a chamber formed therein and a partition in said casing on which partition said chamber is formed, of a valve for closing said chamber, a diaphragm held in said casing below the partition and connected with the stem of the valve, and means for producing the same fluid-pressure in the chamber and on both faces of the diaphragm and means for reducing at times, the pressure on the under 70 side of the diaphragm, substantially as herein shown and described. 75

Signed at New York city, in the county of New York and State of New York, this 26th day of November, A. D. 1900.

HARRY M. SALYER.
